DESIGN FOR A COUCH OR THE LIKE

Joseph W. Bowersox, Glen Ellyn, Ill., assignor to
Superior Felt & Bedding Co., a corporation of
Illinois

Application March 23, 1935, Serial No. 56,006

Term of patent 7 years

To all whom it may concern:

Be it known that I, Joseph W. Bowersox, a citizen of the United States, residing at Glen Ellyn, in the county of Du Page and State of Illinois, have invented a new, original, and ornamental Design for a Couch or the like, of which the following is a specification, reference being had to the accompanying drawing, forming part thereof.

Figure 1 of the drawing is a front elevational view of a couch embodying my design; and Fig. 2 is an end elevational view thereof.

The distinctive feature of my design resides in a base contour which gives to the superstructure the appearance of resting on a frame comprising heavy end pieces resting on the floor and a connecting rail extending between the same on the front side of the couch or the like.

I claim:

The ornamental design for a couch or the like, as shown and described.

JOSEPH W. BOWERSOX.
